Primary Examiner — John A Voytek(74) *Attorney, Agent, or Firm* — Daryl R. Wright; Greg Carr(57) **CLAIM**

I claim the ornamental design for a model vehicle track tread, as shown and described.

DESCRIPTION

FIG. 1 is an upper, left, front perspective view of a model vehicle track tread showing my new design;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view of the model vehicle track tread.

In the drawings, the broken lines illustrate portions of the model vehicle track tread that form no part of the claimed design.
